UNITED STATES PATENT OFFICE.

GEORGE W. STOKES, OF PHILADELPHIA, PENNSYLVANIA.

JACQUARD LOOM.

1,083,303.

Specification of Letters Patent.

Patented Jan. 6, 1914.

Application filed October 1, 1912. Serial No. 723,294.

To all whom it may concern:

Be it known that I, GEORGE W. STOKES, a citizen of the United States, residing at Philadelphia, in the county of Philadelphia 5 and State of Pennsylvania, have invented certain new and useful Improvements in Jacquard Looms, of which the following is a specification.

My invention relates to improvements in 10 Jacquard looms, the object of the invention being to provide an improved mounting for the cards of Jacquard looms, whereby without stopping the loom, certain of said cards may be disconnected from other of said 15 cards and elevated to a position out of the way of the remaining cards, yet in position to be readily returned and used when desired.

Heretofore looms which are particularly 20 designed for weaving carpets and rugs having borders, have been equipped with cards containing a section of border and a section of the body of the carpet or rug. After the border has been woven and a portion of 25 the body, it has been necessary to turn the cards backwardly after each section of the carpet has been woven.

It is the purpose of my invention to provide 30 an improved elevator construction which enables the border cards to be elevated and the ends of the body cards connected, so that an endless series of body cards remain on the loom to permit the body 35 of the rug or carpet to be woven in any length desired, and when the desired length is had, permit the border cards to be again connected with the body cards and the border of the carpet or rug integrally woven at the end of the length. To facilitate this 40 movement and the ready connection and disconnection of the cards, I preferably employ quick detachable fastening devices between the cards which form the subject matter of my application for patent filed March 1, 45 1912 and given Serial No. 680,821.

With these and other objects in view, the invention consists in certain novel features of construction and combinations and arrangements of parts as will be more fully 50 hereinafter described and pointed out in the claims.

In the accompanying drawings: Figure 1 is a diagrammatic view illustrating my improvements in side elevation showing the 55 elevator in its lowest position. Fig. 2 is a similar view showing the elevator in its

highest position. Fig. 3 is a plan view illustrating my improved arrangement of cards which enable the quick connection and disconnection of the same. Fig. 4 is a view in vertical section on the line 4-4 of Fig. 5. Fig. 5 is a view in end elevation on an enlarged scale. Fig. 6 is a fragmentary view in section on an enlarged scale on the line 6-6 of Fig. 5. Fig. 7 is a perspective view 60 of one of the end rod supporting tracks 22 of the elevator, and Fig. 8 is a similar view of one of the intermediate rod supporting tracks 21 of the elevator.

While my invention might be adapted for 70 use on various forms of loom, it is particularly adapted for use in connection with a carpet loom and especially with such a loom designed for weaving rugs and bordered carpets.

I have therefore, illustrated my invention 75 in connection with no particular type of loom, but show diagrammatically in Figs. 1 and 2, a frame 1 to indicate a loom structure having brackets 3 thereon in which the 80 rotary cylinder 4 is mounted to turn, and over this box the cards 5 are adapted to move.

Secured to the ceiling 6 or any other support, and located in a convenient position 85 relative to the loom, preferably above the lay, is my improved rectangular frame which comprises a plurality of vertical hangers 7 secured at their upper ends to the ceiling or other support and connected at 90 their lower ends by transversely positioned horizontal bars 8. I employ as many of these hangers and bars as desired in accordance with the number of sections of cards in use on the loom.

The bars 8 are spaced apart a distance 95 sufficiently greater than the length of the cards to allow the cards to freely swing downwardly between the said bars and the rods connecting the series of cards are supported normally upon the bars 8. I have indicated in Fig. 3, a plan view of my improved arrangement of cards in which I employ snap buttons 9 to connect tapes 10 on the ends of the series of cards 11, and the wires which connect the cards of the several sections, I have given reference numeral 12.

It is to be understood that the border cards at both ends are connected to the body 110 cards by improved quick detachable means, as for example, by the snap buttons, and the

said cards move in order over the cylinder 4, thence downwardly to a position between the bars 8. This movement is guided by inclined bars 13 which may be fixed at their upper ends in any suitable manner and at their lower ends connected to the end bars 8, so that the wires 12 at their ends slide upon the inclined bars 13, and find lodgment and rest upon the bars 8.

10 As the wires collect on the bars 8, they are moved forwardly by the accumulation of wires back of the same and the cards from the forward end of the sections pass over an idle roller 14, and thence back to the 15 cylinder 4. The end bars 8 are also connected to the ceiling or support 6 by means of parallel vertical guide bars 15, the latter having guide recesses 16 in their inner faces as clearly shown in Fig. 6.

20 I-bars 17 are mounted to slide between the guide bars 15, and these I-bars 17 are preferably made up of three separate and distinct strips which are secured by transverse rivets 18. The smaller strip or intermediate 25 member of the I-bar, slides between the bars 15, while the inner member of the I-bar slides in the grooves 16 and is substantially flush with the inner face of guide bars 15.

The I-bars 17 are connected at their lower 30 ends by strips 19 with vertical wire supports 20. One of these wire supports is shown most clearly in Fig. 8. At their upper ends, they are elongated transversely forming tracks 21 which curve downwardly 35 at their ends to form sharp edges joining the edges of bars 8.

The vertical wire supports 20 are preferably formed of a single piece of sheet metal extended transversely between their ends 40 and bent to form the tracks 21, the two ends of the wire supports positioned at opposite sides of the bars 8, and preferably of a length to maintain the connecting strips 19 out of the way of the cards hanging from 45 the wires as clearly shown in Fig. 4. While I have illustrated three of these intermediate wire supports, it is to be understood that as many may be provided as are necessary to accommodate between the end bars 8 the 50 desired number of sections of cards.

The I-bars 17, in line with tracks 21, are provided with tracks 22. These tracks 22 have integral downwardly projecting lugs 55 24 and 25, the former adapted to be secured to the I-bars, and the latter adapted to engage the inner face of the end bars 8, so as to support the tracks 22 directly above the end bars 8. In other words, the tracks 21 and 22 are in alinement and positioned directly 60 above the bars 8. In fact, the tracks 21 and 22 when in position on the bars 8, constitute a part of the surface upon which the wires 12 ride and are supported.

The I-bars 17 are connected by a transverse 65 bar 23 which is positioned above the

tracks 21 and 22 sufficiently to allow the wires to move freely thereunder.

The I-bars 17, strips 19, tracks 21 and 22, and bar 23 constitute an elevator which moves vertically and is guided between the bars 15. This elevator is balanced by means of a weight 26, the latter being connected by ropes 27 with bar 23, said ropes passed over pulleys 28 as indicated in Fig. 4. In other words, the weight is designed to balance the elevator, so that it will require but little power to move the same.

To operate the elevator, I provide levers 29 which are secured between their ends upon a shaft 30, and the latter mounted in 80 brackets 31 depending from the ceiling. These levers 29, at one end, are connected by links 32 with the lower ends of the I-bars 17, and at least one of these levers, at its other end, is provided with a depending rope 33 85 which terminates in position to be readily grasped by the operator.

Any suitable means, may of course be provided to positively hold the elevator in its highest position if desired, but the elevator may be nicely balanced by means of the weight 26, so that it will, under normal 90 conditions, remain in any position to which it is moved.

The operation is as follows: In weaving 95 a rug, the intermediate lengths of the rug are formed with border sections at the ends of the lengths, and the body portion between the bordered ends. The cards on the loom, when the weaving operation begins, present first for operation, the cards forming the border and then a short length of the body. These cards for the body are then used over again as many times as it is desired according to the length of the rug, and then the 100 border cards are again brought into operation. With my improvements, as soon as the border is formed, the cards which form the same will be positioned over the elevator with the wires 12 of such cards supported upon the tracks 21 and 22. The operator then disconnects the border cards from the body cards and moves the elevator to lift the border cards out of the way. He then connects the ends of the body cards and permits the loom to operate repeating the body cards as many times as desired, because they are connected together and form an endless chain of cards. When the desired length of body is woven, the end cards of the body 110 cards are disconnected and connected to the end cards of the border cards, so that the border may be woven in again at the end of the length.

By means of a structure of this kind, it 115 will be noted that the border cards may be taken out at any time desired, that the body cards may be used over and over again without any necessity of turning the cards backward as is necessary with looms in general 120 130

use, and by providing the cards with quick detachable means such as explained, this operation may be readily carried out.

Various slight changes might be made in 5 the general form and arrangement of parts described without departing from my invention, and hence I do not limit myself to the precise details set forth, but consider myself at liberty to make such changes and 10 alterations as fairly fall within the spirit and scope of the appended claims.

Having thus described my invention, what I claim as new and desire to secure by Letters Patent is:

- 15 1. A card supporting attachment for Jacquard looms, comprising guides, and an elevator movable in said guides and adapted to support certain of the cards, substantially as described.
- 20 2. A card supporting attachment for Jacquard looms comprising horizontal bars adapted to receive the card supporting rods, and an elevator adapted to receive and elevate certain of said card supporting rods, 25 substantially as described.
- 30 3. A card supporting attachment for Jacquard looms, comprising hangers, horizontal bars supported by the hangers, rod supports, tracks on the rod supports normally positioned on the said bars, devices connecting said rod supports forming an elevator, means for guiding the vertical movement of the elevator, and means for moving the elevator, substantially as described.
- 35 4. A card supporting attachment for Jacquard looms, comprising hangers, horizontal bars supported by the hangers, rod supports, tracks on the rod supports normally positioned on the said bars, devices connecting said rod supports forming an elevator, means for guiding the vertical movement of the elevator, pulleys supported above the elevator, a weight, flexible devices connecting the weight and the elevator, a lever ful-
- 40 45 crumed between its ends, and a link connecting one end of said lever with the elevator, substantially as described.
- 50 5. The combination with a Jacquard loom, of a series of cards, and movable means adapted to support certain of said cards out of the path of the movement of other of said cards, substantially as described.
- 55 6. The combination with a Jacquard loom, of a series of cards, detachable means between certain of said cards, and movable means adapted to support certain of said

cards out of the path of movement of the other of said cards, substantially as described.

7. The combination with a Jacquard loom, 60 of a series of cards, detachable connecting means between certain of said cards, and an elevator adapted to move certain of said cards out of the path of movement of other of said cards, substantially as described. 65

8. The combination with a Jacquard loom, 70 of a series of cards, wires at regular intervals between the cards and extending at their ends beyond the cards, horizontal bars receiving the said wires thereon, and an elevator supported on the bars and receiving the wires, said elevator adapted to move certain of said wires and the cards carried thereby out of the path of movement of the other of said cards, substantially as de- 75 scribed.

9. The combination with a Jacquard loom, 80 of a series of cards, wires at regular intervals between the cards and extending at their ends beyond the cards, horizontal bars receiving the said wires thereon, and an elevator supported on the bars and receiving the wires, said elevator adapted to move certain of said wires and the cards carried thereby out of the path of movement of the 85 other of said cards, said tracks having inclined ends, whereby the rods ride upon the tracks, substantially as described.

10. The combination with a Jacquard loom, 90 of vertical guide bars, an elevator mounted to move in said guide bars, and tracks on said elevator adapted to receive and support the wires of Jacquard loom cards, substantially as described.

11. The combination with a Jacquard 95 loom, of vertical guide bars, an elevator mounted to move in said guide bars, tracks on said elevator adapted to receive and support the wires of Jacquard loom cards, means balancing the weight of the elevator, 100 and means for moving the elevator whereby certain of said wires and the cards carried thereby may be elevated out of the path of movement of the other of said cards, substantially as described. 105

In testimony whereof I have signed my name to this specification in the presence of two subscribing witnesses.

GEORGE W. STOKES.
